COMBINED DESK, LOCKER AND BUNK BED UNIT

Anthony A. La Rocca and Shirley L. La Rocca, both of 18 Partridge Ave., Somerville, Mass. 02145

Filed July 19, 1967, Ser. No. 7,873

Term of patent 14 years

(Cl. D5—4)

FIG. 1.

FIG. 2.

FIG. 1 is a perspective view of a combined desk, locker and bunk bed unit taken from one corner thereof showing two sides and the top thereof; and

FIG. 2 is a perspective view of a combined desk, locker and bunk bed unit taken from the corner opposite that of FIG. 1, to show the remaining sides thereof.

We claim:

The ornamental design for a combined desk, locker and bunk bed unit, as shown.
